WINE RACK

Edward A. Wagschal, New York, N.Y., assignor to
Recycled Plastic Products Corp., Bronx, N.Y.

Filed Nov. 9, 1971, Ser. No. 197,193

Term of patent 14 years

Int. Cl. D7—99

U.S. Cl. D6—188

FIG. 1

FIG. 2

FIG. 3

FIG. 4

FIG. 5

FIG. 1 is a front perspective view of a wine rack according to the present invention and showing the wine rack as a three-unit module;

FIG. 2 is a front sectional view of the wine rack of FIG. 1 taken substantially along the line 2-2 of FIG. 1 and looking in the direction of the arrows;

FIG. 3 is an alternative embodiment of a wine rack according to the present invention and showing a five-unit module thereof;

FIG. 4 is a further alternative embodiment of a wine rack according to the present invention and showing a three-unit module thereof in a laterally expanded arrangement; and,

FIG. 5 is a still further alternative embodiment of a wine rack according to the present invention and showing a five-unit module thereof in a vertically expanded arrangement.

I claim:

The ornamental design for a wine rack, as shown and described.
